CLAIM

The ornamental design for an exercise apparatus, as shown and described.

DESCRIPTION

FIG. 1 is a rear perspective view of the claimed design; FIG. 2 is a front view of the claimed design of FIG. 1; FIG. 3 is a rear view of the claimed design of FIG. 1; FIG. 4 is a right view of the claimed design of FIG. 1; FIG. 5 is a left view of the claimed design of FIG. 1; FIG. 6 is a top view of the claimed design of FIG. 1; and, FIG. 7 is a bottom view of the claimed design of FIG. 1. The broken lines illustrate portions of the exercise apparatus that form no part of the claimed design.
